UNITED STATES PATENT OFFICE.

JERVIS R. HARBECK, OF DETROIT, MICHIGAN, ASSIGNEE, BY MESNE ASSIGNMENTS, TO
DETROIT CAN COMPANY, OF DETROIT, MICHIGAN, A CORPORATION OF NEW
JERSEY.

CONTAINER-CLOSURE.

970,496.

Specification of Letters Patent. Patented Sept. 20, 1910.

Application filed October 12, 1908. Serial No. 457,229.

To all whom it may concern:

Be it known that I, JERVIS R. HARBECK, a citizen of the United States, and residing at Detroit, in the county of Wayne and State of Michigan, have invented a new and useful Container-Closure, of which the following is a specification.

This invention relates to container tops and its object is to provide a sealing gasket whereby the closure of a container top may be rendered fluid tight without the use of solder.

This invention consists of a closure having a substantially cylindrical portion, a stiffening flange at one end of the cylindrical portion, a disk closing the other end, and a circumferential groove formed in the cylindrical portion between the disk and the flange; together with a container head provided with a cylindrical flange extending inwardly; an annular gasket of flexible material, which is also preferably elastic, fitted into the groove in the closure; the parts being so proportioned that when the closure is pressed into the opening in the head the gasket will form a vapor tight joint between the cylindrical flange and the head and the cylindrical portion of the closure.

In the accompanying drawing Figure 1 is a plan of a container top provided with this improved closure. Fig. 2 is an elevation of a container with a part of the upper portion broken away to show the manner of securing the head and closure in position. Fig. 3 is an enlarged detail of this construction in cross section.

Similar reference characters refer to like parts throughout the several views.

In the drawings 1 is the body of the container having a bottom 2 of any desirable type. The head 3 is formed with a circular portion 4 to receive the upper edge of the body. The head is provided with an inwardly extending, substantially cylindrical flange 5. The closure has a substantial cylindrical portion 6 provided with an inwardly extending beaded or grooved portion 7, and a disk 8 closing the lower end. At the upper end of the cylindrical portion is an outwardly extending radial flange 9 which has its edge turned inwardly in order to stiffen it. A gasket 10, preferably in the form of a rubber band, is placed in the groove in

the cylindrical portion 6 of the closure and should be of such size that it slightly projects beyond the cylindrical wall. The cylindrical portion 6 of the closure should be of such size that it will just slip into the flange 5 of the head. When the gasket is placed in position and the closure is pushed down into place, the gasket will be compressed.

In Fig. 3 the flange 5 is shown as being of such length that it will extend but little below the upper edge of the groove in the closure. In this case the gasket upon expanding will bulge out below the lower edge of the flange 5, as shown in the drawing, and thus hold the closure in position and at the same time absolutely seal the joint between the flange and the cylindrical portion 6 of the closure. To remove the closure a sharp instrument is inserted between the head 3 and the radial flange 9 and the closure pried out which usually results in destroying the gasket.

While the body of the closure and the flange 5 have been described as cylindrical, it is sufficient that they be merely substantially so. A slight taper is not objectionable. The cylindrical form is preferred as a polygonal is more difficult to form although it may be employed if desired.

This style of gasket is particularly adapted for sealing containers intended for deliquescent chemicals, baking powder, dehydrated vegetables and other articles which are to be kept dry, but any other material or form may be employed.

Having now explained my improvements, what I claim as my invention and desire to secure by Letters Patent is:

1. In a container, the combination of a head having an inwardly extending flange, a closure comprising a flanged body having a circumferential groove so positioned that when the closure is in place the lower edge of the flange on the head will be opposite said groove, and a gasket in said groove partially projecting over the lower edge of said flange.

2. In a container, the combination of a head having a downwardly extending cylindrical flange, a closure comprising a cylindrical portion having one end closed and having a circumferential groove so posi-

tioned that when the closure is in place, the lower edge of the flange on the head will be opposite said groove, and a flexible gasket seated in said groove and partially projecting over the lower edge of said flange to seal the joint between the closure and head.

In testimony whereof, I have signed this

specification in the presence of two subscribing witnesses.

JERVIS R. HARBECK.
